(57) **CLAIM**

The ornamental design for a packaging tray as shown and described.

DESCRIPTION

FIG. 1 is a perspective view of a packaging tray showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an unfolded interior view thereof;

FIG. 10 is a perspective view showing the packaging tray in a use state; and,

FIG. 11 is another perspective view showing the packaging tray in a use state.

The evenly broken lines represent parts of the article that form no part of the claim. The dot-dash broken lines represent fold lines that form no part of the claim.

1 Claim, 11 Drawing Sheets
